FOOD SLICER

Norman B. De Hart, Winston-Salem, N. C., assignor to De Hart Manufacturing Company, Winston-Salem,
N. C., a corporation of North Carolina

Application June 18, 1957, Serial No. 46,629

Term of patent 14 years

(Cl. D89—1)

I claim:

The ornamental design for a food slicer, as shown.
